UNITED STATES PATENT OFFICE.

EDWARD TINKHAM GIBSON, OF MATAWAN, NEW JERSEY.

AMMUNITION-CARRIER.

No. 801,076.

Specification of Letters Patent.

Patented Oct. 3, 1905.

Application filed June 8, 1905. Serial No. 264,302.

To all whom it may concern:

Be it known that I, EDWARD TINKHAM GIBSON, a citizen of the United States, residing at Matawan, in the county of Monmouth and State of New Jersey, have invented a new and useful Improvement in Ammunition-Carriers, of which the following is a specification.

My invention relates to certain improvements in the construction of ammunition-carriers in which the ammunition is suspended across the body from one shoulder.

During a prolonged engagement it becomes necessary to furnish soldiers from time to time with additional ammunition to replace that which they have expended. The exigencies are such as to make it desirable that the quantity intended for each soldier be issued in a way which admits of the soldier quickly obtaining his allotted amount and quickly settling it upon his person.

The first object of my invention is to provide a shoulder-supported ammunition-carrier which possesses the good feature of a bandoleer which so carries the ammunition that none of it comes between the arm of the wearer and his body, and thereby relieves the brachial nerve and artery from the injurious pressure and poundings which they sustain when the ammunition is carried as in an ordinary bandoleer.

The second object of my invention is to provide a shoulder-supported carrier comprising a package-bearing piece, supporting means, and securing means, which admits of the said package-bearing piece being detached and discarded when the supply of packages borne on it is exhausted and replaced by a duplicate package-bearing piece bearing a fresh supply of packages, said supporting means comprising a body-band carrying package-bearing-piece-fastening means, said securing means comprising waist-belt-fastening means adapted to attach the carrier to a waist-belt, said package-bearing piece consisting of a piece provided along its length with package-holders constructed to hold packages (consisting of clips or magazines of cartridges, or packages consisting of pasteboard boxes containing ammunition, or packages consisting of the articles for first aid to the wounded which hospital-corps soldiers carry, or packages consisting of the small articles for personal use which a soldier now carries in his "blanket-roll") and provided 55 with end-fastening means detachably engag-

ing with said package-bearing-piece-fastening means, and said securing means adapted to retain said body-band in working position on the body of the wearer when the said package-bearing piece is detached from the carrier, and thereby admit of said package-bearing piece being detached and thrown away when the ammunition held in its package-holders is exhausted and replaced at any time by a duplicate package-bearing piece bearing a fresh supply of ammunition or of being detached and laid aside if it is desired to replace a package-bearing piece bearing the soldier's personal articles by a package-bearing piece bearing ammunition; and the third object of my invention is to provide package-holders which cost so little to prepare that the piece on which they are fashioned may be thrown away when the contents of the package-holders is exhausted.

The invention consists in certain novel constructions and combinations of parts, as will be hereinafter described, and pointed out in the claims.

In the drawings, Figure 1 is a front perspective view of a carrier constructed on the lines of my present invention. Fig. 2 exhibits the carrier shown in Fig. 1 in use. In this figure the carrier is illustrated unprovided with package-holders and cartridge-covering strip and the waist-belt in use with the carrier is one having pockets. Fig. 3 is a front perspective view of the body-band of the carrier shown in Figs. 1 and 2, the package-bearing piece and the cartridge-covering strip having been detached. Fig. 4 is a view of a transverse section of an extremity of the package-bearing piece shown in Figs. 1 and 2. Fig. 5 is a perspective view of a section of the package-bearing piece shown in Fig. 1, showing in full view a package-holder fashioned to hold a package consisting of a clip of cartridges. Fig. 6 is a perspective view of the section of the package-bearing piece shown in Fig. 5 with the cord-loops of the package-holder removed, this figure showing in full view the wire-formed bullet-sockets and loop-holders which enter into the construction of the package-holders fashioned on opposite surfaces of the package-bearing piece in Figs. 1 and 5. Fig. 7 is a perspective view of a modification of the package-holder when fashioned to hold a clip of cartridges. Fig. 8 is a view of a portion of a waist-belt provided with a fixed ring for a point of attach-

ment for the waist-belt-fastening means on the rear end of the carrier. Fig. 9 is a view showing the waist-belt-fastening means for the rear end of the carrier as consisting of a 5 double hook, which is adapted to engage with points of attachment on the length of a waist-belt, (only a portion shown,) the points of attachment consisting of openings formed in the fabric of the belt. Fig. 10 is a view of 10 a transverse section of a package-bearing piece, showing that by fastening the package-holders to hold clips of cartridges with their clip ends adjacent to the same edge of the package-bearing piece a piece may be 15 employed which is much narrower than that which is shown in Figs. 1, 5, and 6. Fig. 11 is a perspective view of a package-bearing piece provided with package-holders fashioned to hold packages consisting of paste- 20 board boxes containing clips or magazines of ammunition, and in this figure one of the package-holders is represented as holding such a package. Fig. 12 is a view of a transverse section of a package-bearing piece having 25 a holder fashioned to hold a package consisting of a box and showing the loop-holder carried on the fabric of the package-bearing piece. Fig. 13 is a front view of a modification of the body-band of my carrier in use in 30 connection with the suspenders which are now employed in the United States Army to support the ammunition waist-belt. Fig. 14 is a perspective view of the body-band of a carrier to which my improvements are applied. 35 Fig. 15 is a front perspective view showing the lower end of the front portion of the body-band shown in Fig. 14 as it appears when secured to a waist-belt. Fig. 16 is a perspective view of a carrier improved on the 40 lines of my present invention. Fig. 17 is a perspective view of a modification of the bullet-socket. Fig. 18 is a perspective view of a modification of the end-fastening means on an end of a package-bearing piece and of a 45 modification of the package-bearing piece fastened on a portion of a body-band. Fig. 19 is a view of a modification of the bullet-socket.

In the following specification the term 50 "body-band" will not be employed in the sense of its meaning a continuous strip of some band material, but in the sense of its meaning the combination of pieces which enter into the construction of the body feature of the invention, which feature has the general conformation of a "band."

In Figs. 1, 2, and 3, A is the front portion, and A' the back portion, of a piece consisting of a strip which in these figures forms the 60 body-band of the ammunition-carrier and which is preferably formed of woven fabric two and one-fourth inches wide. The said front portion A has an extension α folded back to form a loop α' , which is held in the 65 embrace of a sliding loop α'' , and the said back

portion has an extension α^3 folded back to form a loop α^4 , which is held in the embrace of a sliding loop α^5 . The object of these folded extensions α and α^3 is primarily to permit of the lengthening and shortening of the body-band to fit the wearer, and in order that the free ends of the said extensions may be detachably secured to desired points along the length of the body-band the said free ends are provided with suitable fastening devices, the 70 end of the extension α being provided in this instance with a well-known fastening device consisting of a double hook α^6 , adapted to engage with eyelets α^7 , and the end of the extension α^3 provided with a similar double hook α^8 , 75 adapted to engage with eyelets α^9 . The said extension α^3 is slidably engaged on a bearing in a link B, which carries securing means consisting of a waist-belt fastener consisting in this instance of a hook C. When this body- 80 band is in use, (see Fig. 2,) it is suspended upon the front and back of the body from one shoulder with its ends carried to separate points of attachment on the length of a waist-belt D and 85 separately attached thereto, the lower end of 90 the said front portion A being in this instance attached to the waist-belt D by sliding one of the buckle ends of the waist-belt through the loop α' , (which loop serves to form a suitable "waist-belt fastener,") and the lower end 95 of the said back portion A' being attached to the waist-belt by passing the waist-belt fastener C downward between the waist-belt and the wearer's body and hooking it over the lower edge of a waist-belt, (the pockets α , 100 Fig. 2, which exist on the United States Army ammunition-belts, affording shoulders against which the said hook C may bring up) the space in advance of each pocket affording a 105 suitable point of attachment for this particular waist-belt fastener C. In said Figs. 1 and 110 2 the package-bearing piece U is provided on its opposite extremities with end-fasteners E and E', consisting of hooks in this instance, and in Fig. 1 is provided between its said extremities with package-holders F, dividing a portion of the length of the said piece into 115 holder-sections. In Fig. 1 the portion α of the package-bearing piece is intended to rest upon the shoulder of the wearer and is therefore left clear. The package-holders F (hereinafter fully described) are fashioned on both the front and back surfaces of the package-bearing-piece U, and each is illustrated as being 120 fashioned to hold a package consisting of a clip of cartridges, G representing the clip end, and α the bullet end, of a clip of cartridges. The said end-fastener E detachably engages with a bearing on a package-bearing-piece 125 fastener H, which is carried on the said front portion A of the body-band and which package-bearing-piece fastener in this instance consists of a link which passes through eyelets α , and the said end fastener E' detachably engages with a bearing i on a package- 130

bearing-piece fastener I, which is slidably carried on the said back portion A' of the body-band and which package-bearing-piece fastener in this instance consists of a sliding link 5 which has in addition to the said bearing i a bearing i' , on which is slidably engaged an adjusting-strip J, one end of which is secured to the said back portion A' by rivets j and the other end of which is provided with fastening means j' , which in this instance is a well-known one, consisting of a hook adapted to engage with eyelets j'' . The object of the said adjusting-strip J is to provide the carrier with adjusting means whereby the distance 10 on the length of the body-band between the said package-bearing-piece fasteners may be increased and diminished to adapt the said package-bearing-piece fasteners to hold a package-bearing piece in a fully-extended and 15 tensely-drawn state when on the body of a wearer.

The carrier illustrated in Fig. 1 is shown provided with a cartridge-covering strip X, (its central portion being broken away in the 20 figure,) which is adapted to extend over and cover the exposed clips of cartridges (to prevent their glistening) and which has its forward end portion slidably engaged on a bearing in a double link X' , carried on the loop a' , and its rear end attached to a link X'' , slidably carried on the adjusting-strip J.

In the carrier illustrated in Fig. 1 it will be seen that as the end-fasteners E and E' are similar and the package-bearing-piece fasteners H and I are similar the package-bearing piece U may be detached from the body-band when the contents of the package-holders on the front portion of the carrier are exhausted and reattached to the body-band in a reversed 35 position, and it will also be seen that when the entire contents of the package-holders is exhausted the package-bearing strip may be detached and thrown away, and, furthermore, it will be seen that in this carrier 40 the body-band is so secured on the body of the wearer by securing means (which in this instance consists of the described waist-belt-fastening means) that it is retained in a working position on the body of the wearer when 45 the package-bearing piece is detached from the carrier and that at any time a duplicate package-bearing piece bearing another supply of packages may be attached to the package-bearing-piece fastening means on the 50 body-band.

An inexpensive and neat way of finishing the extremities of the package-bearing piece U is shown in Figs. 1, 2, and 4, which latter figure shows two folds of an extremity of a 55 package-bearing piece U, (formed in this instance from a strip of woven fabric,) held in a fold e of a plate which forms the end-fastener E and which plate is secured to said extremity by rivets, one of which, e' , is shown.

60 Each of the package-holders on the said pack-

age-bearing piece U in Fig. 1 is formed as is the package-holder F, which is shown in detail in Fig. 5—that is to say, the package-holder F comprises in its construction a bullet-socket K, which in this instance carries a loop-holder L and short sections of a length of cord M, which are held at their ends in such relation to the package-bearing piece as to form a group of loops m' , m'' , m''' , and m''' on one of the surfaces of a section of the length 70 of the said package-bearing piece.

The bullet-socket K, which is shown in full view in Fig. 6, is formed from a piece of moderately-pliable wire bent to provide a base k , having two arms k' and k'' , on one of which 80 an eye or loop k''' is formed and the other of which is divided to form two arms k''^4 and k''^5 . This bullet-socket K is secured to the package-bearing strip U by its base k , which transfixes the fabric of the strip, and by the legs k''^4 85 and k''^5 , which are bent upon the said fabric, as shown in Fig. 6, (or as shown in Fig. 10,) and the said eye or loop k'''' is adapted to receive the bullet end of one of the cartridges in a clip of cartridges and bring up against a 90 shoulder on the said cartridge to prevent displacement of the clip of cartridges in the direction of its bullet end.

The loops m' , m'' , m''' form in the package-holder F socket-loops which are adapted to 95 receive the bodies of the cartridges and prevent displacement of the clip of cartridges in the directions of its sides, and the loop m'''' forms a cover-loop, which is adapted to be extended across the clip end of the clip of cartridges and prevent displacement of the latter in the direction of its clip end. The said group of loops is formed, as has been stated, 100 from a length of cord M, the said cord being passed (by means of a needle) forward and backward through the fabric of the package-bearing strip at proper points on a section of the length of the same to divide the length of the cord into short sections, which are adapted to form loops which admit of being 105 brought against a given package to bind the package against the said strip and to prevent its displacement in the directions of the legs of the loops. The said loops m' , m'' , m''' , and m'''' have their legs slidably held in the fabric 110 of the package-bearing strip, so that the cover-loop m'''' may be drawn to cause a shortening of the length of the legs of the socket-loops m' , m'' , m''' and consequent binding of the 115 embraced clip of cartridges against the said strip by the said socket-loops, and the said cover-loop m'''' is held tightly drawn by being engaged with the loop-holder L.

The loop-holder L in my package-holder has a base l , by which it is secured to the part 120 which carries it in the package-holder, and the said base supports a hook-forming tongue l' . In the described package-holder F the base l (see Fig. 6) of the loop-holder L is attached to the bullet-socket K, as the loop- 125

130

holder and the bullet-socket K are conveniently formed together from a short length of wire which is bent to form these parts.

The metal from which the loop-holder is formed is pliable in order that its hook-forming tongue l' (see Fig. 6) may be bent from the extended position in which it is shown in dotted outline in Fig. 6 to the hook-forming position shown in full outline. The said hook-forming tongue of the loop-holder is not bent to form a hook until the loop which is to be held by it is placed within the grasp of the said tongue, and then the said tongue is bent at such point on its length as will serve to hold the loop in a tautly-drawn state, and the said tongue is readily unbent by the soldier's fingers when he desires to extract the ammunition from the package-holder.

In Figs. 1 and 5 I show the said cover-loop m^4 as being caught over the front corners of the clip G; but this is only necessary in the case of clips which have such frail catches g' , Fig. 5, that additional means should be employed to insure the retention of the clip G on the heads of the cartridges.

When there is no necessity for holding the clip G against sliding movement, the legs of the cover-loop m^4 may be simply brought over the body of the clip, as is illustrated in Fig. 7, in which figure I also show that the metallic bullet-socket K, Figs. 5 and 6, may be dispensed with and the bullet-socket K' be fashioned by forming a socket from coils of the loop m^5 , which is formed from a short section of the length of cord which forms the other loops in the package-holder.

If the package-holder shown in Fig. 7 is employed, the described loop-holder will be attached to the bullet-socket K' by its base, which will be bent (as is the base l of the loop-holder L in Fig. 11) to form an eye through which the said coils of the loop m^5 will be threaded.

As has been explained, the hook C, Fig. 1, will serve as a suitable waist-belt fastener to retain the lower end of the back portion A' of the body-band at the desired point on the length of the waist-belt if the said belt is one which is provided with pockets or thimbles.

If, however, the waist-belt is not provided with pockets or thimbles, a ring N, Fig. 8, adapted to receive the said hook, may be permanently secured to a suitable point on the length of the upper edge of the waist-belt to afford a point of attachment. Furthermore, if so desired, the carrier may retain its feature whereby the waist-belt fastener on its rear end is adapted to be adjusted to points of attachment along the length of a waist-belt by providing the belt (see Fig. 9) with openings d' , adapted to receive the hooked ends of waist-belt fastener N', consisting of a double hook, which is carried on a piece N of the body-band of the carrier, said piece N consisting of a ring which is carried by the

piece O next adjacent to it in the length of the body-band, said piece O in the figure consisting of a snap-hook which is carried on a link B, having a bearing on which the next adjacent piece A¹⁵ in the length of the body-band is slidably engaged.

In Figs. 1 and 5 the package-bearing piece U is as wide as the cartridges are long, as this width (which will be three and one-half inches) is made necessary when clips of cartridges are carried in reversed positions on the opposite surfaces of the package-bearing piece. A saving of material may be made, however, by fashioning the package-holders to hold the clips of cartridges with their clip ends adjacent to the same edge of the package-bearing piece, as is illustrated in Fig. 10, as this will only require a package-bearing piece U' two and one-half inches wide.

If the package-holder is to be fashioned to hold ammunition put up in pasteboard boxes, it will be fashioned on the lines illustrated in Fig. 11, in which a package-bearing piece U² (provided on its upper extremity with an end-fastener E², consisting of a link, and on its lower extremity with an end-fastener E, consisting of a hook) is provided with two package-holders each consisting of loop-holders L L and L and of short sections of a length of cord which are held at their ends in such relation to the package-bearing strip E⁴ as to form a group of loops m^6 , m^7 , m^8 , m^9 , m^{10} , and m^{11} on the front surface of the said package-bearing piece. The said loop m^6 is secured to the base l of one of the loop-holders L and is adapted to be secured to the said loop m^7 by the hook-forming tongue l' of its loop-holder to form a socket-loop which is adapted to receive a pasteboard box R, containing cartridges put up in clips G, and prevent displacement of the said box in the directions of its ends. The said loop m^8 is secured to the base of another loop-holder L, while the loop m^9 is secured to the base of still another loop-holder L, and both are adapted to be brought against the bottom of the said pasteboard box to prevent displacement of the said box in the direction of the said bottom and held in this engagement by means of the hook-forming tongues of their respective loop-holders L, which are adapted to engage the cover-loops m^{10} and m^{11} , (which latter when thus engaged are adapted to prevent displacement of the said box in the direction of its mouth.) To form the loops, as shown in the said Fig. 11, the cord is passed (by means of a needle) forward and backward through the fabric of the package-bearing strip at the required points, and to prevent the legs of the loops sliding in the fabric stitches are taken.

In Fig. 11 the pasteboard box R is illustrated with half of the cover R' removed, as I shall urge that ammunition-boxes to be used in connection with my ammunition-carrier have their covers divided by an incision, so

as to admit of one-half of it (or whatever portion of it covers a tier of ammunition) being removed to expose the clips or magazines covered by it.

- 5 In arranging the group of loops for a package-holder intended to hold a box containing clips or magazines of ammunition arranged in tiers in the box, as are the clips G in the box R, the cover-loops (m^{10} and m^{11}) have their 10 legs engage with the fabric of the package-bearing strip at such points as will place one of the said cover-loops in such position in the package-holder as to adapt the cover-loop to be brought across one-half of the length of 15 the cover of the box which the package-holder is constructed to hold and as will place the other one of the said cover-loops in position to be brought across the other half of the said cover, as by this arrangement the package-holder will admit of a tier of clips or magazines being extracted from the said box without jeopardizing the safety of the remaining 20 clips or magazines.

Without departing from my invention the 25 described cover-loops in a package-holder fashioned to hold a box may instead of engaging with the hook-forming tongue of a loop-holder, which is secured by its base, as in Fig. 11, to an opposed loop, engage, as illustrated in Fig. 30 12, with the hook-forming tongue of a loop-holder L', which is secured by its base to the fabric of the package-bearing strip U². In this Fig. 12 R² is a box, m^{12} is a cover-loop, and L' is a loop-holder consisting in this instance of the well-known eyelet-hook which is seen on shoes.

In the modifications of the body-band of my carrier (shown in Fig. 13) the package-bearing-piece fastener H² consists of a bearing on 40 a waist-belt fastener P, which consists of a double hook having hook ends which engage with openings h', formed in the waist-belt D, to afford a point of attachment for the said waist-belt fastener P, and the package-bearing-piece fastener I', consisting in this instance of a snap-hook, is carried on the upper end of a piece A², (consisting of a strip of pliable material,) which forms a part of the body-band in this instance. The said piece A² is 45 provided with securing means, consisting of a loop A³, which is slidably carried on said piece and which is adapted to be engaged by one of the shoulder-bands S of the suspenders S' (which at the present time are in use in the 50 United States Army to support ammunition waist-belts) to retain the upper portion of the said part A² of the body-band in position on the shoulder of the wearer. The said piece A² has an extension a¹¹, folded back to form a 55 loop, which is held in the embrace of a sliding loop a¹², the object of this extension a¹¹ being to permit of the lengthening and shortening of the body-band to support the said strip-fastener I' on the body of the wearer at 60 a suitable distance from the said strip-fas-

tener H² to adapt the two said strip-fasteners H² and I' to engage end-fasteners (such as E and E², which exist on the package-bearing strip U² in Fig. 11) to support a suitable package-bearing piece on the front of the wearer's 70 thorax. The said extension a¹¹ is slidably engaged on a bearing in a link A⁴, which has a bearing on which a piece consisting of an adjusting-strip J' is slidably engaged. The extension j⁴ of the said adjusting-strip J' is in 75 this instance provided with a hook j', adapted to engage with eyelets j², and the lower end of the piece J' is attached to a link which carries a snap-hook O, carrying a ring N, which carries securing means consisting of the waist-belt fastener N', hereinbefore described, which is secured to the waist-belt D. 80

In the modification illustrated in Figs. 14 and 15 I show my improvements applied to the body-band of an ammunition-carrier which 85 is constructed on the lines of my United States Patent No. 667,082 of January 29, 1901, in so far as it is constructed to be worn suspended from the shoulder with the two portions on the front of the body held at an angle with 90 each other, the angle being near the waist-line and has means in connection with the angle for retaining the band in position on the front of the body. My improvements are applied to the body-band of this just-mentioned 95 carrier in the following way: The piece A⁵, which when the body-band is in use will come upon the front of the body from beneath the arm-pit, is provided with an extension a¹³, which is slidably engaged on a bearing in a link A⁴ and has a well-known sliding fastener a¹⁴ on its end. The said link A⁴ 100 is carried on the rear end of a piece A⁶, which is adapted to extend over the shoulder of the wearer and then downward on the front of 105 his body. This said piece A⁶ is provided with a package-bearing-piece fastener I', consisting of a snap-hook in this instance, and with an adjusting extension a¹⁵, which is slidably engaged on a bearing in a link a¹⁷, which is 110 held in a sleeve a¹⁶, carried on the upper part of the forward end of the said piece A⁶ of the body-band, and a package-bearing-piece fastener H', consisting of a link, is carried on 115 the end of the waist-belt fastener T, which 120 consists of a hook carried on the lower part of the front end of the said piece A⁶ opposite the said link a¹⁷.

As illustrated in Fig. 15, the waist-belt fastener T is adapted to be passed downward between the waist-belt D and the body of a wearer and hooked over the lower edge of the belt D to not only hold the body-band in position on a wearer, but to place the said package-bearing-piece fastener H' in a position 125 adapted to admit of a suitable end-fastener, such as E in Fig. 11, on the lower end of a package-bearing piece, being attached to it to hold the said lower end in position when the 130 said package-bearing piece is suspended on the

portion A⁶ of the body-band by the attachment of its upper end-fastener, such as E² in Fig. 11, to the strip-fastener I', which is shown in Fig. 14.

5 In the body-band illustrated in Fig. 14 the said extension a¹³ is provided to admit of alterations being made in the length of the body-band, and the adjusting extension a¹⁵ is provided to admit of the distance between the 10 said package-bearing-piece fasteners H' and I' being increased or diminished, the said adjusting extension a¹⁵ being provided on its end with an adjustable fastener, which in this instance is the well-known one consisting of the 15 hook j', which is adapted to engage with eyelets j².

In the modification illustrated in Fig. 16 I show my improvements applied to an ammunition-carrier, which is also constructed on the 20 lines of my said patent in so far as it is composed of two portions pivotally attached to each other at both extremities and adapted to be worn suspended across the body from one shoulder and to admit of the two portions on 25 the front of the body being brought to an angle with each other and held in this position by a waist-belt fastener. My improvements are applied to this just-mentioned ammunition-carrier in the following way: The piece 30 A⁷ of the body-band is provided with an extension a¹⁷, which is slidably engaged on a bearing in a link A⁸ and has a well-known sliding fastener a¹⁴ on its end. The said link A⁸ is carried on a link-holding piece A⁹, which is 35 pivotally secured to an end of the portion A¹⁰ of the body-band by the pivot V, (a loose rivet.) The said portion A¹⁰ is provided with an extension a¹⁸, which is slidably engaged on a bearing in a link A¹¹ and has a sliding fastener a¹⁹ on its end. The said link A¹¹ is 40 carried on a link-holding piece A¹², which is pivotally secured to a piece A¹³ by the pivot V', (a loose rivet.) The said piece A¹³ carries a link A¹⁴, which has a bearing on which an adjusting extension a²⁰ of the said piece A⁷ is 45 slidably engaged, and the said adjusting extension a²⁰ is provided on its end with a suitable adjustable fastener, which in the present instance consists of a hook which is adapted 50 to engage with eyelets j². The said piece A¹³ carries a package-bearing-piece fastener H, which in the present instance consists of a link, and the said portion A⁷ carries a companion package-bearing-piece fastener I', which in the present instance consists of a 55 snap-hook. The said package-bearing-piece fastener H detachably engages with an end-fastener E (in the present instance consisting of a hook) on an end of a package-bearing piece U⁴, which on its other end is provided with an end-fastener E², (in the present instance consisting of a link,) which detachably engages with the said package-bearing-piece fastener I', and the said package-bearing piece U⁴ is provided with package- 60

holders (not shown in Fig. 16) adapted to hold packages consisting in the present instance of clips of cartridges G, which in Fig. 16 are illustrated as being borne on both surfaces of the said package-bearing piece U⁴. 70 At the pivoted point of connection between the said piece A⁹ and the said piece A¹⁰ the body-band is provided with a waist-belt fastener W, consisting of a hook which is adapted to be hooked over the lower edge of a waist-belt to hold the two portions of the body-band on the front of the wearer's body at an angle with each other, (thereby placing the package-bearing piece U⁴ in a position which would bring it on the back of the wearer's body,) and at the pivoted point of connection between the said piece A¹³ and the piece A⁷ the body-band is provided with a waist-belt fastener W', consisting of a hook (swiveled in the same sleeve with the package-bearing-piece fastener H in the present instance) which is adapted (when the body-band is turned on the body of the wearer to bring the said package-bearing piece U⁴ upon the front of the wearer's body) to be hooked over 80 the lower edge of a waist-belt to hold the said package-bearing piece U⁴ in a position on the front of the wearer's body, wherein it extends from the waist-belt nearly vertically to the supporting-shoulder. 85

In the modification illustrated in Fig. 16 the described extensions a¹⁷ and a¹⁸ are provided to afford means for lengthening and shortening the body-band, and the described adjusting extension a²⁰ is provided to admit 90 of the distance between the said package-bearing-piece fasteners H and I' being increased and diminished. When a package-bearing piece is to be provided on both its front and back surfaces with the described 95 package-holders for holding clips of cartridges, it is possible that the cost of its manufacture may be lessened by forming the two oppositely-disposed bullet-sockets from one piece of metal on the lines of the bullet-socket shown in Fig. 17, in which a piece of sheet metal is represented as being bent to provide a base k⁶, having two arms k⁷ and k⁸, on one of which a sleeve k⁹ is formed and on the other a sleeve k¹⁰ is formed, each of said 100 sleeves k⁹ and k¹⁰ being adapted to receive the bullet ends of two of the cartridges in a clip of cartridges (and bring up against a shoulder on the cartridges) in order that a loop-holder L may be formed integral with each sleeve 105 (only shown formed with one in Fig. 17) in a position adapted to bring it between the said two cartridges and also in order that the bullet-socket may be secured to the package-bearing piece U⁵ by a rivet or eyelet-rivet X. 110 Furthermore, the cost of the manufacture of the package-bearing pieces may be lessened by employing end-fasteners, formed as is the end-fastener E² on the package-bearing piece U⁶ in Fig. 18, which end-fastener consists 115 120 125 130

of two eyelets which are adapted to be detachably engaged on the package-bearing-piece fastener I^2 , which has a double hook for this purpose. Until required for use the 5 sockets k^3 and the loop-holders L of the wire-formed bullet-socket K on a package-bearing piece will be bent to lie flat against the fabric of the said piece.

It is intended that package-bearing pieces 10 provided with package-holders for holding packages of ammunition shall be manufactured and stored away for use when the soldiers are required to go into action and that pending that event the body-band of the improved ammunition-carrier shall be worn by 15 the soldier to support a package-bearing piece which is provided with package-holding means adapted to hold the articles for personal use which the soldier now carries in his 20 blanket-roll and which I will call a "personal package-bearing piece." When the soldier goes into action, the said personal package-bearing piece will be detached from the body-band and replaced by a package-bearing piece 25 bearing ammunition. Furthermore, the described package-holder for holding a package consisting of a clip of cartridges is adapted to hold two clips of cartridges in the same holder, if desired, by employing in place of 30 the bullet-socket K a bullet-socket K^2 , which is illustrated in Fig. 19, and only differs from the said bullet-socket K in having an additional loop or eye k^{11} , formed in advance of the loop or eye k^3 .

35 The cord which is employed in my package-holder may be a spun cord, a metallic cord, or a cord consisting of narrow tape.

Having thus described my invention, what I claim as new, and desire to secure by Letters 40 Patent, is—

1. A carrier consisting of a bandoleer provided with package-holders for holding packages on the thorax of the wearer; said carrier provided on its ends with waist-belt-fastening means and constructed to be worn suspended 45 upon the front and back of the body from one shoulder with said ends carried at the same time to separate points of attachment on the length of a waist-belt and separately attached thereto by said waist-belt-fastening means; said waist-belt-fastening means being adapted to engage at said points to hold the said bandoleer at an angle with said waist-belt when in use, and comprising a waist-belt fastener 50 adapted to be detached from and attached to its one of the said points of attachment on the said belt; said package-holders disposed on a portion of said bandoleer to divide the length of said portion into holder-sections, and each 55 of said package-holders comprising means adapted to be extended across the mouth of the package-holder to retain a package in said holder; said bandoleer comprising a pliable band having a folded extension of itself slidably 60 engaged on a bearing in the length of 65

the bandoleer, and said folded extension provided on its end with fastening means adapted to be adjusted to points along the length of said pliable band to lengthen and shorten the bandoleer.

2. A carrier consisting of a bandoleer provided with package-holders for holding packages on the thorax of the wearer; said carrier being provided at its ends with waist-belt-fastening means and adapted to be worn suspended 70 upon the front and back of the body from one shoulder with said ends carried to separate points of attachment on the length of a waist-belt and for separate attachment thereto by said waist-belt-fastening means; said waist-belt- 75 fastening means being adapted to engage at said points to hold the said bandoleer at an angle with said waist-belt when in use, and comprising a waist-belt fastener adapted to be adjusted to points along the length of said waist-belt; said package-holders disposed on a portion of said bandoleer to divide the length of said portion into holder-sections, and each 80 of said package-holders comprising means adapted to be extended across the mouth of the package-holder to retain a package in said holder; said bandoleer comprising a pliable band having a folded extension of itself slidably 85 engaged on a bearing in the length of the bandoleer, and said folded extension provided on its end with fastening means adapted to be adjusted to points along the length of said pliable band to lengthen and shorten the bandoleer.

3. A carrier consisting of a bandoleer provided with package-holders for holding packages on the thorax of the wearer; said carrier provided on its ends with waist-belt-fastening means and constructed to be worn suspended 90 upon the front and back of the body from one shoulder with said ends carried at the same time to separate points of attachment on the length of the waist-belt, and separately attached thereto by said waist-belt-fastening means; said waist-belt-fastening means being 95 adapted to engage with said points to hold the said bandoleer at an angle with said waist-belt when in use, and comprising a waist-belt fastener adapted to assume a hooked engagement with its point of attachment on said belt; said package-holders disposed on a portion of said bandoleer to divide the length of said portion into holder-sections, and each of said package-holders comprising means adapted to be extended across the mouth of the package-holder 100 to retain a package in said holder; said bandoleer comprising a pliable band having a folded extension of itself slidably engaged on a bearing in the length of the bandoleer, and said folded extension provided on its end with fastening means adapted to be adjusted to points along the length of said pliable band to 105 lengthen and shorten the bandoleer.

4. A carrier consisting of a bandoleer constructed to be worn suspended upon the front 110

and back of the body from one shoulder for holding packages on the thorax of the wearer; said carrier comprising a body-band, a package-bearing piece, package-bearing-piece fasteners, and securing means, said package-bearing piece provided on its opposite extremities with end-fasteners, and between its said extremities with package-holders dividing a portion of the length of the said piece 5 into holder-sections and said package-bearing piece being held in the carrier by the attachment of its said end-fasteners to said package-bearing-piece fasteners, said end-fasteners adapted to be detached from and attached 10 to said package-bearing-piece fasteners, said securing means comprising waist-belt-fastening means whereby the carrier may be secured to a waist-belt, and said securing means being adapted to secure the said body-band and the 15 said package-bearing-strip fasteners in working position on the body of the wearer when the said package-bearing piece is detached from the said package-bearing-piece fasteners.

5. A carrier comprising a body-band, package-bearing-piece fasteners, and a package-bearing piece, said body-band constructed to be worn suspended upon the front and the back of the body from one shoulder, and provided with waist-belt-fastening means where- 20 by it may be secured to suitable points of attachment on the length of a waist-belt, said body-band comprising a pliable band having a folded extension of itself slidably engaged on a bearing in the length of the body-band, 25 and said folded extension being provided at its end with fastening means adapted to be adjusted to points along the length of said pliable band to lengthen and shorten the body-band, said package-bearing-piece fasteners 30 carried on said body-band, said package-bearing piece provided on its extremities with end-fasteners detachably engaging with said package-bearing-piece fasteners, and on a portion of its length between said extremities with 35 means for holding packages.

6. A carrier consisting of a bandoleer constructed to be worn suspended upon the front and back of the body from one shoulder with its ends carried to a waist-belt, for holding 40 packages on the thorax of the wearer, said carrier comprising a body-band and a separately-formed package-bearing piece, said package-bearing piece provided on its extremities with end-fastening means and between 45 said extremities with package-holding means, said body-band provided with waist-belt-fastening means whereby it is attached to a waist-belt, a package-bearing-piece fastener adapted to assume a hooked engagement with the 50 end-fastening means on one of the said extremities of said package-bearing piece, and said body-band comprising in its length a pliable band having a folded extension of itself slidably engaged on a bearing in the length 55 of the body-band to permit of increasing and

diminishing the length of the body-band, and said folded extension being provided at its end with fastening means adapted to be adjusted to points along the length of said pliable band.

7. A carrier consisting of a bandoleer for holding packages on the body of the wearer, said carrier comprising a body-band, a package-bearing piece, and package-bearing-piece fasteners, said package-bearing piece being 70 provided on its opposite extremities with end-fasteners and between its said extremities with package-holders dividing a portion of the length of the said piece into holder-sections, said package-bearing piece held in the carrier 75 by the attachment of its said end-fasteners to said package-bearing-piece fasteners, said end-fasteners adapted to be detached from and attached to said package-bearing-piece fasteners, said body-band comprising a pliable band and adjusting means, said pliable band comprising a folded extension of itself slidably engaged on a bearing in the length of the carrier to admit of the carrier being lengthened and shortened, said adjusting 80 means consisting of means for increasing and diminishing the distance separating the said package-bearing-piece fasteners in the length of the carrier.

8. A carrier for cartridges and the like comprising a body-band, means at the ends of said band for securing the same in connection with the body of a wearer, a package-bearing piece extending longitudinally along the body-band, fastening devices at the ends of the 90 package-bearing piece for securing the same to the body-band, and means for securing packages to the package-bearing piece, substantially as set forth.

9. The combination with a bandoleer adapted to extend over the shoulder of a wearer, means at the ends of said bandoleer whereby the same may be secured to devices on the body of the wearer, a package-bearing piece extending longitudinally along the bandoleer 100 and provided at its ends with fastening devices and cooperating fastening devices on the bandoleer, the package-bearing piece being adapted for reversal end to end upon the bandoleer, and devices adjacent to the opposite ends of the package-bearing piece for securing the packages to said bearing-piece, substantially as set forth.

10. The combination in a carrier substantially as described of a body-band, a package-bearing piece extending longitudinally along the body-band, a fastening device at one end of the package-bearing piece, a fastening device on the body-band, and an adjustable strap secured at one end to the body-band and 110 passed at its free end through the fastening device on said package-bearing piece and having its said free end adjustably secured, substantially as and for the purpose set forth.

11. In a carrier for carrying packages on the 115

body of the wearer, the combination with a supporting piece or strip, and with loop-holding means, of cord passed in opposite directions through a section of the length of said 5 supporting-piece to form on a surface of said section a group of loops having their legs arranged in such relations to the surfaces of a given package as to adapt said loops to be brought against said package to prevent displacement of the package in the directions of said legs, and said loop-holding means consisting of means for detachably holding said loops against said package.

12. The combination in the carrier substantially as described of a body-band, a package-bearing piece having end-fastening devices and adapted for detachable connection with said body-band, and means on the package-bearing piece for detachably securing the 10 packages thereto, substantially as set forth.

13. A carrier adapted to be worn suspended upon the front and back of the body from one shoulder, said carrier comprising package-bearing-piece fasteners, a package-bearing piece provided at its extremities with means whereby it is detachably attached to said package-bearing-piece fasteners and provided along a portion of its length between said extremities with package-holders dividing said 25 portion into holder-sections, means whereby said package-bearing-piece fasteners are securely held in operating position on the body of the wearer when said package-bearing piece is detached from said package-bearing piece fasteners, and the last said means comprising waist-belt-fastening means whereby the carrier is attached to the wearer's waist-belt, said package-holders each consisting of means adapted to hold a package on said strip, 30 said package-bearing-piece fasteners consisting of means detachably engaging with the said means on the ends of said package-bearing piece and said package-bearing-piece fasteners disposed in the carrier to place them 35 in a position wherein, when the carrier is in use they are adapted to hold said package-bearing piece in a position in which it is mainly located above the lower edge of the wearer's belt and has its long diameter on a 40 plane which forms an angle with the plane of the lower edge of said waist-belt.

14. A carrier for carrying packages on the body of a wearer, said carrier comprising a strip of woven material provided on its extremities with fastening means and on a portion of its length with package-holders, said package-holders comprising a package-holder composed of loops, and loop-holding means, said loops formed from short sections of a 45 length of cord having their ends held in such relation to a surface of said strip and to each other as to form on said surface a group of loops, said loops having their legs arranged in such relations to the surfaces of a given 50 package as to adapt said loops to be brought

against said package to prevent displacement of the package in the directions of said legs, and said loop-holding means consisting of means for detachably holding said loops against said package.

70

15. A carrier for carrying packages on the body of a wearer, said carrier comprising a strip of woven material provided with package-holders, means whereby the length of the carrier may be increased and diminished and 75 means whereby the carrier may be held in position on the body, said package-holders comprising a holder comprising in its construction loop-holding means and short sections of a length of cord held at their ends in 80 such relation to a surface of said strip and to each other as to form on said surface a group of loops, said loops having their legs arranged in such relation to the surfaces of a given package as to adapt said loops to be brought 85 against said package to prevent displacement of the package in the directions of said legs; and said loop-holding means consisting of means for detachably holding said loops against said package.

90

16. A carrier for carrying packages on the body of a wearer, said carrier comprising a strip of woven material provided with package-holders, means whereby the length of the carrier may be increased and diminished, and 95 means whereby the carrier may be held in position on the body, said package-holders comprising loop-holding means, and short sections of a length of cord held at their ends in such relation to a surface of said strip and 100 to each other as to form on said surface a group of loops, said loops having their legs slidably held on their points of attachment and arranged in such relation to the surfaces of a given package as to adapt said loops to 105 be drawn to tightly embrace said package to prevent displacement of the package in the directions of said legs, and said loop-holding means consisting of means for detachably holding said loops against said package.

110

17. A carrier for carrying packages on the body of the wearer, said carrier comprising a strip of woven material and a package-holder comprising in its construction loop-holding means and short sections of a length 115 of cord held at their ends in such relation to a surface of said strip and to each other as to form on said surface a group of loops, said loops being arranged in such relation to the surface of a given package as to adapt said 120 loops to be brought against said package to prevent displacement of the package in the directions of the sides of said loop and said loop-holding means comprising a loop-holder consisting of a metallic piece having a base 125 by which it is secured to the part which carries it in the package-holder and a hook-forming tongue adapted to assume a hooked engagement with one of said loops.

18. The combination with a carrier adapted 130

- to be worn by a soldier, of a package-holder comprising in its construction a loop formation having the ends of its legs held on a surface of the carrier in such relation to each other 5 as to form said loop formation into a socket-loop adapted to receive a given package to prevent displacement of the same in the directions of its sides, a loop having the ends of its legs held on a line approximately parallel with 10 the direction of said socket-loop and in such relation to the ends of the legs of said loop formation and to said package as to form a cover-loop adapted to be brought against an end of said package to prevent its displacement 15 in the direction of said cover-loop, means for preventing displacement of the said package in the direction of its other end, and loop-holding means for detachably holding said cover-loop against said package.
- 20 19. The combination with a carrier adapted to be worn by a soldier, of a package-holder comprising in its construction a loop formation having the ends of its legs held on a surface of the carrier in such relation to each other 25 as to form said loop formation into a socket-loop adapted to receive a given package to prevent displacement of the same in the directions of its sides, a loop having the ends of its legs held on a line approximately parallel with 30 the direction of said socket-loop and in such relation to the ends of the legs of said loop formation and to said package as to form a cover-loop adapted to be brought against an end of said package to prevent its displacement 35 in the direction of said cover-loop, means for preventing displacement of the said package in the direction of its other end, and loop-holding means for detachably holding said cover-loop against said package, said loop-holding means consisting of a metallic loop-holder having a base by which it is secured to the part which carries it in the package-holder and a hook-forming tongue adapted to assume a hooked engagement with said cover-loop.
- 40 20. In a package-holder for holding a clip of cartridges on a carrier constructed to be worn by a soldier, a loop formation adapted to embrace the shell portion of a clip of cartridges to prevent displacement of the latter in the directions of its sides, a loop having its legs held at the clip end of said holder, a loop-holder adapted to assume a hooked engagement with the last said loop to prevent displacement 45 of a clip of cartridges in the direction of its clip end, and a metallic bullet-socket held at the bullet end of said holder and adapted to prevent displacement of a clip of cartridges in the direction of its bullet end, said loop-holder adapted to detachably secure the second said loop to said bullet-socket.
- 50 21. A package-bearing piece for carriers having a body-band and constructed to be worn by a soldier, said piece consisting of a strip of woven material provided at its ex-

tremities with end-fastening means adapted to detachably engage with package-bearing-piece fastening means carried on the body portion of the carrier, and said piece having a portion of its length between said extremities provided with package-holders, said package-holders comprising a package-holder having cord loops in its construction, the ends of the legs of said loops being held in such relation to each other as to dispose them at 75 points on said portion on lines at angles with each other.

22. In a package-holder for carriers constructed to be worn by soldiers, a metallic loop-holder in combination with parts comprising a loop formed from cord, said loop-holder adapted to assume a hooked engagement with said loop to hold said loop over a part of a package.

23. In a package-holder for carriers constructed to be worn by soldiers, a metallic loop-holder in combination with parts comprising a short length of cord, said loop-holder adapted to assume a hooked engagement with said cord to prevent exit of a package from the mouth of the package-holder.

24. In combination with a package-bearing portion of a carrier constructed to be worn by a soldier, a package-holder adapted to hold a package consisting of a clip of cartridges, said package-holder comprising means adapted to prevent displacement of said package in the directions of its sides and clip end, and means adapted to prevent displacement of said package in the direction of its bullet end, the last 100 said means consisting of a device made from metal and formed to provide a loop or eye adapted to engage with points on the bullet-end part of said package, said loop or eye carried on an arm of a base which intersects the 105 planes of the front and back surfaces of the back of the package-holder and which base has another arm which is bent at approximately a right angle with said base.

25. A package-holder for holding a package consisting of a clip of cartridges in said package-holder comprising in its construction, a loop adapted to embrace the shell portion of a clip of cartridges to prevent displacement of the said clip of cartridges in the directions 115 of the legs of said loop, a loop having the ends of its legs held at the clip end of the package-holder, a loop-holder adapted to assume a hooked engagement with the last said loop to prevent displacement of the said clip of cartridges in the direction of its clip end, and a bullet-socket held at the bullet end of the package-holder, said bullet-socket adapted to receive the bullet end of a cartridge in said clip and bring up against a shoulder on said cartridge to prevent displacement of the said clip of cartridges in the direction of its bullet end.

26. A package-holder for securing a clip of cartridges on the package-bearing portion of 130

a carrier constructed to be worn by a soldier, said package-holder comprising a loop adapted to admit of its legs being brought across the clip end of a clip of cartridges, and a metallic device for the bullet end of the clip of cartridges; said metallic device having a loop or eye to receive the bullet end of a cartridge and an extending pliable portion adapted to be bent into hooked engagement with the loop brought across the clip end of the clip of cartridges.

27. In a package-holder for securing a clip of cartridges on the package-bearing portion of a carrier constructed to be worn by a soldier, a loop having the ends of its legs held to points on said package-bearing portion, and a metallic device having means for engaging the bullet end of a cartridge in a clip of cartridges; said metallic device having an integrally-extending portion adapted to secure said loop for holding the clip of cartridges against movement in the direction of its clip end.

28. In a carrier comprising a row of package-holders adapted to support packages of cartridges on the body of a wearer, a cartridge-

covering strip longitudinally held in the carrier by suitable fastening means and adapted to extend in front of said package-holders to prevent the sun's rays striking the cartridges, 30 said cartridge-covering strip adapted to permit of the removal of said packages and retain its position in front of said package-holders.

29. A carrier constructed to be worn by a soldier, comprising package-bearing-piece fasteners, means adapted to support said package-bearing-piece fasteners in working position on the body of a wearer, a package-bearing piece provided on its extremities 40 with end-fasteners detachably engaging with said package-bearing-piece fasteners and provided along its length with a row of package-holders adapted to hold packages of cartridges, and cartridge-covering means held in the carrier and adapted to extend in front of said package-holders to prevent the sun's rays striking the cartridges. 45
